UNITED STATES PATENT OFFICE.

JOSEPH GRIGAS, OF SHENANDOAH, PENNSYLVANIA.

DELIVERY BOX.

Application filed July 11, 1922. Serial No. 574,137.

To all whom it may concern:

Be it known that JOSEPH GRIGAS, a citizen of the United States, residing at Shenandoah, in the county of Schuylkill and State of Pennsylvania, has invented new and useful Improvements in Delivery Boxes, of which the following is a specification.

This invention relates to receptacles, and more particularly to a receptacle adapted to receive containers such as bottles containing milk, cream, or other liquids, and to lock the same therein.

The invention has as its object the provision of a receptacle of this type adapted to be mounted upon the outside of a home or lodging so that it is not necessary for the delivery man to place the bottles openly on the outside of the house, as is now customary.

20 A more specific object of the invention is to afford a receptacle of this type having means whereby the receptacle may be locked only after the door with which it is provided is closed, and then only when a bottle 25 or other container is placed therein.

A still further object is to provide an adjustable means whereby containers of varying weight and size may be selectively required to lock the container.

30 The invention further contemplates the provision of indicating means in order to indicate the character of the container required to operate the locking means.

Other objects of the invention, such as 35 simplicity of construction, economy in manufacture, and ease of operation, will become obvious as the description proceeds.

In the accompanying drawings, there is shown one embodiment of the invention, 40 and in said drawings:

Fig. 1 is a perspective view showing the device in position.

Fig. 2 is a top plan view with top removed.

45 Fig. 3 is a vertical section on the line 3-3 of Fig. 2, looking in the direction of the arrows.

Fig. 4 is a rear elevational view showing the operating mechanism.

50 Fig. 5 is a side elevational view with a portion of the casing removed.

Fig. 6 is a side elevational view similar to Fig. 5.

55 Fig. 7 is an elevational view of the operating mechanism, showing the same ad-

justed for quart bottles, and before a bottle is placed in the receptacle.

Fig. 8 is a view similar to Fig. 7, showing the operating parts in locked position.

Fig. 9 is a cross sectional view on the line 9-9 of Fig. 7.

Fig. 10 is a sectional detail of the means for bearing the spring resistance to the movement of the container supporting platform.

Fig. 11 is a detail view of the indicating means, and

Fig. 12 is a detail view showing a position of the operating mechanism.

Referring to the drawings for a more detailed description, 10 indicates generally a casing having an interior semi-cylindrical wall 11 spaced from the outer wall of the casing, the inner wall forming a compartment 12 the front of which is provided with a closure member or door 13 pivoted or hingedly secured to the casing, as at 14. The casing is provided with a bottom 15 (Fig. 3) and a top 16 which serve to close the compartment 12. Arranged within the compartment is a vertically movable container supporting platform or floor 17 which is supported by means of a substantially U-shaped rod 19 having upwardly extending leg portions passing through guides 20 upon the casing and upwardly through the top 16 of the casing where the terminals of the rod are connected by a strip 21 spaced slightly above the top 16 of the compartment 12.

As will be noted from an inspection of Figs. 2 and 3, the portion of the rod 19 connecting the legs thereof extends beneath the platform 17, as indicated at 19', and the platform is normally maintained in the raised position shown in Fig. 3 by means of yielding supporting means, such as springs 22 connecting to lugs 23 upon the supporting rod 19 and to lugs 24 upon the casing. Obviously, when a container, such as a bottle of milk, is placed in the compartment 12 and upon the platform 17, it depresses the platform in opposition to the tension of the springs 22.

In order to lock the receptacle, a laterally projecting latch arm 25 (Figs. 7 and 8) is positioned upon one of the legs or rods 19 and is adapted to engage a hook 26 upon the interior of the door 13 when the platform and its latch arm are depressed. A lock

27 operable from the exterior of the casing (Fig. 6) is positioned below the arm 25 on the casing and has an upwardly extending slotted arm 28 through which passes 5 a lug 29 upon the latch arm 25. As will be noted in Fig. 7, when there is no container in the compartment 12, the lug 29 is at the upper end of the slot in arm 28 of the lock, but upon depression of the platform, the lug moves to the lower end of the slot, as shown in Fig. 8, and when the door is to be opened, upward movement of the arm 28, by means of a key inserted in the lock, causes the lower end of the slot 10 to engage the lug 29 and to lift the platform and the latch arm 25 to release the latter from the hook 26 upon the door.

The invention also contemplates the provision of means for preventing the platform 20 17 and the latch arm from being depressed until the door is closed. For this purpose, there is mounted upon the top 16 of the compartment a substantially curved or bell crank lever 30, one end of which is connected at 25 31 to an arm 32 extending through the casing and secured to the top of the door, as at 33. The lever 30 is fulcrumed upon a stud 34 and has its opposite ends secured to a spring 35 anchored at 36 upon the top of 30 the compartment 12 and normally maintaining the door closed. The lever 30 is provided with an upstanding lug 37 (Figs. 2, 3 and 7) which, when the door is opened, is carried beneath the strap 21 connecting 35 the terminals of rod 19 which supports the platform. When the door is opened and the lug 37 is beneath the strap 21, the platform cannot be lowered, since the strap rests upon the lug 33, but upon the closing of the door and the return of the parts to the position shown in Fig. 2, the weight of the container upon the platform depresses the latter and causes latch arm 25 to come into engagement with the hook 26 upon the interior of the door. The door operating mechanism, above described, may be enclosed by a cap plate 10' spaced above the top of the compartment 12 and forming part of the casing.

50 In order that the device may be adjustable for the reception of bottles of various sizes and weights, such as pints, quarts, etc., means is provided for varying the yielding resistance to the depression of the supporting platform 17 whereby containers of different weights may selectively be required to depress the platform the necessary distance to bring the latch arm 25 into engagement with the door hook 26. For this purpose, there is fixedly secured upon the interior of the casing a channel bar 39 (Figs. 8 and 10) normally registering with a channel bar 40 upon the platform supporting rod 19. Within the channel bars slides 55 a bolt 41 having an upwardly extending

arm 42 to which is secured a spring 43 anchored at its opposite end to the lug 24 upon the top of the compartment. The arm 42 of the bolt passes between the fingers 44 of the forked end of an operating lever 45 pivoted at 46 to the compartment wall and having an operating finger 47 projecting through an arcuate slot 48 to the interior of the compartment 12. As shown in Fig. 7, the bolt 40 is positioned in channel bar 41, and, as thus positioned, when the platform is lowered, spring 43 supplements the springs 22 and opposes depression of the platform. Obviously, by moving the lever 45 by means of its operating finger 47 to the opposite end of slot 48 from its position when the parts are as shown in Fig. 7, the bolt 41 is moved within the channel bar 39 which is fixed to the casing. With the bolt in this position, the platform may be lowered without drawing downwardly the bolt 41 or tensioning the spring 43. Additionally, the bolt 41 may be moved to an intermediate position so that it projects partially into the channel bar 40 and partially into the channel bar 39, as indicated in Fig. 12. In this position, the bolt prevents depression of the platform, even though the door is closed, since it will be recalled that the channel bar 39 is fixedly secured to the casing.

In order to indicate the character of the container necessary to depress the platform and to lock the door when the latter is closed, an indicator 50 (Fig. 11) is positioned so as to be visible from the exterior of the casing through an opening 51 in the casing. The indicator is shown as supported upon the end of a curved rod 52 extending downwardly and upwardly through a bracket 53 upon the interior of the casing wall and having an inwardly projecting terminal portion 54 above the operating lever 45. A spring 55 secured to the end of the rod 52 and anchored upon a lug 56 upon the casing above the indicator normally maintains the indicator in its upper position shown in Fig. 6, so that the legend "pint milk" is visible through the opening 51 in the casing. The terminal 54 of the indicator supporting rod 52 extends beneath the arm 57 of a bell crank lever which is fulcrumed at 58 upon the wall of the compartment 12 and has a downwardly projecting arm 59 engaging the operating lever 45. Movement of the operating lever from the position shown in Fig. 5, wherein the bolt 41 is in the fixed channel bar 39 so that the spring 43 does not oppose downward movement of the platform 17, will move the bell crank lever arm 57 downwardly. If the operating lever is moved to the extreme right, as shown in Fig. 8, the bolt 41 is moved into the channel bar 40 so as to throw the spring 43 into channel bar 40 to resist depression of the

supporting platform. At the same time, the indicator 50 is depressed so as to bring the legend "1 quart milk" into view through the opening 51. Obviously, if the operating lever is moved to an intermediate position with the bolt 41 extending partially into the channel bar 39 and partially into the channel bar 40 so that the platform cannot be depressed, the indicator is likewise moved 10 to an intermediate position, wherein the legend "No milk today" is visible through the opening 57.

It will thus be clear that the receptacle can be set so as to require for the locking 15 of the same the insertion therein of containers of varying weights. If the container is intended particularly for the reception of milk bottles, as disclosed in the embodiment of the invention herein set 20 forth, the legends upon the indicator will preferably be as shown in the drawings, although these may be modified to suit the preference of the user. If the user does not wish any milk to be positioned in the 25 receptacle, the operating lever is adjusted so that the bolt 41 is in the position shown in Fig. 12, and the indicator will, at the same time, be vertically adjusted so that the legend "No milk today" is visible. If 30 the deliverer of the milk should not notice the indicator, he will naturally make sure that the receptacle cannot be locked when the door is open, for the reason that the lug 33, upon the door operating lever 37, is 35 positioned beneath the strap 21, preventing the depression of the platform. When the door is closed, the platform is locked against depression by means of the bolt 41, and, therefore, the receptacle cannot be locked. 40 If the delivery man should fail to observe the particular amount of milk desired and indicated upon the legend, and should attempt to leave a pint of milk when a quart is desired, the weight of the pint container 45 will not suffice to lower the latch arm 25 into engagement with the door hook 26, since the spring 43 will oppose downward movement of the platform supplementing the springs 22, the bolt 41 being, at this 50 time, in the position shown in Fig. 8 within the channel bar 40.

After a bottle of milk has been left by the delivery man, it is simply necessary, in order to open the container, for the user to 55 insert a key in lock 27 and movement of the key raises the lock arm 28 which will lift the platform and the latch arm, permitting the door to be opened.

It should be understood that numerous 60 modifications may be made in the illustrated and described structure without departing from the scope of the invention which is definitely set forth in the following claims, and the limits of which are 65 defined in the prior art.

I claim:

1. A safety receptacle comprising a vertically movable container support, spring means opposing downward movement of said support under the influence of a container, a member adapted to confine a container upon said support, locking means operatively connected to said support, for locking said confining member in operative position when said support is depressed, and means for varying the spring resistance to the downward movement of said support whereby containers of different weights may selectively be required to cause said locking means to lock said confining member. 70 75

2. A safety receptacle comprising a vertically movable container support, spring means opposing downward movement of said support under the influence of a container, a member adapted to confine a container upon said support, locking means operatively connected to said support for locking said member in operative position when said support is depressed, and means for rendering said locking means inoperative when the confining member is in operative position. 80 85 90

3. A safety receptacle comprising a vertically movable container support, spring means opposing downward movement of said support under the influence of a container, a confining member adapted to hold a container upon said support, locking means operatively connected to said support for locking said member in operative position when said support is depressed, means for varying the spring resistance to the downward movement of said support whereby containers of different weights may selectively be required to cause said locking means to lock said confining member, and means for rendering said locking means inoperative when the confining member is in operative position. 95 100 105 110

4. A safety receptacle comprising a vertically movable container support, spring means opposing downward movement of said support under the influence of a container, a closure member for said receptacle, locking means operatively connected to said support for locking said closure in closed position when said support is depressed, an indicator for indicating the size of container to be placed upon said support, said indicating means having in association therewith means for varying the spring resistance to the downward movement of said support thereby requiring placing upon the support of containers of the weight called for by said indicating means before the locking means can be operated. 115 120 125

5. A safety receptacle comprising a movable container support, yielding means opposing movement of said support under the 130

influence of a container, a confining member adapted to retain a container upon said support, locking means operatively connected to said support for locking said member in operative position when the support is depressed, and means for selectively maintaining said locking means against operation until the containers of predetermined weights are placed thereon.

10. 6. A safety receptacle as specified in claim 5, said receptacle having means for rendering said locking means inoperative when the confining member is in operative position.

7. A safety receptacle comprising a vertically movable container support, yielding means for opposing downward movement of said support under the influence of a container, a confining member adapted to retain a container upon said support, locking means operatively connected to said support for locking said confining member in operative position when said support is depressed, an indicator for indicating the size and weight of the receptacle to be placed upon said support, and means in association with said indicating means for preventing operation of said locking means unless a container of the predetermined weight and size indicated by said indicating means is placed upon said support.

8. A safety receptacle as specified in claim 7, said indicating means being adapted to indicate that no container is to be placed upon said support, and the means in association with said indicating means being adapted to prevent operation of said locking means when the indicator is so adjusted even though the confining member is in operative position.

40. 9. A safety receptacle comprising a vertically movable container support, spring means opposing downward movement of said support under the influence of a container, a confining member adapted to retain a container upon said support, locking means operatively connected to said support for locking said confining member in operative position when said support is depressed, an indicator for indicating the size and weight of receptacle to be placed upon said support, and means for varying the spring resistance and the downward movement of said support in direct ratio to the weight of the receptacle indicated by said indicator whereby said locking means will not be operated unless the container of the size and weight indicated is placed upon said support.

10. A safety receptacle as specified in claim 9, said indicator being adapted to indicate that no container is to be placed upon said support, and means in association with said indicator for locking the support against movement and thereby to prevent operation of said confining member locking means when the member is in operative position.

11. A safety receptacle comprising a casing, a door for said casing, a vertically movable container supporting platform in said casing, spring means for supporting said platform, said platform being depressible under the weight of a container in opposition to said spring means, locking means connected to said platform and vertically movable therewith, means on said door adapted to be engaged by said locking means when the platform is depressed and the door is closed, means for preventing depression of said platform and movement of said locking means until the door is closed, and means adapted selectively to be thrown into operation for preventing depression of said platform and actuation of said locking means when the door is closed.

12. A safety receptacle comprising a casing, a door for said casing, a vertically movable container supporting platform in said casing, spring means for supporting said platform, said platform being depressible under the weight of a container in opposition to said spring means, locking means connected to said platform and vertically moveable therewith, means on said door adapted to be engaged by said locking means when the platform is depressed and the door is closed, means for varying the spring resistance to the movement of said platform whereby containers of varying weights may selectively be required to move said locking means into engagement with said means upon the door, manually operable means for actuating said spring-resistance varying means, an indicator adjustable by said manually operable means to indicate the character of the container required to move said locking means to operative position.

13. A safety receptacle as specified in claim 12, said means for varying the spring resistance being also adapted to lock said platform against depression when the door is closed.

In testimony whereof I have hereunto set my hand.

JOSEPH GRIGAS.
